UNITED STATES PATENT OFFICE.

MAURICE W. WHITE, OF SOMERVILLE, MASSACHUSETTS, ASSIGNOR OF
ONE-HALF TO GEORGE W. ROSS, OF SAME PLACE.

VIOLIN.

SPECIFICATION forming part of Letters Patent No. 350,962, dated October 19, 1886.

Application filed November 9, 1885. Serial No. 182,189. (No model.)

To all whom it may concern:

Be it known that I, MAURICE W. WHITE, of Somerville, county of Middlesex, and State of Massachusetts, have invented an Improvement 5 in Stringed Instruments, of which the following description, in connection with the accompanying drawings, is a specification, like letters on the drawings representing like parts. This invention has for its object to improve 10 the construction of stringed instruments, whereby the cord by means of which the tail-piece is connected with the usual peg is free from contact with the face of the instrument, thereby permitting the face to vibrate its full 15 capacity unsubdued by the contact of the cord, which usually is drawn taut and directly over the edge of the face of the instrument; also to provide a stringed instrument of the class upon which chin-rests are employed with an im- 20 proved chin-rest which is so constructed as to be entirely free from contact with the face of the instrument, and when employed also allows the face of the instrument to vibrate its full capacity, thereby enhancing the quality 25 and fullness of the tone.

The invention consists in the combination, with the body of a stringed instrument, the tail-piece, and cord by means of which the tail-piece is attached to the said body, of a peg to 30 which the said cord is attached, and an interposed projection or shoulder rising therefrom, over which the cord passes and upon which it bears when drawn taut, thereby freeing the face of the instrument from contact with the 35 cord; also, in the combination, with the body of a stringed instrument, its tail-piece, and cord, of a peg and an interposed projection or shoulder rising therefrom, over which the cord passes and upon which it bears when drawn 40 taut, and a chin rest or support secured to the said projection or shoulder, thereby preventing either the cord or chin rest or support from coming in contact with the face of the instrument; also, in the combination, with the body 45 of a stringed instrument, its tail-piece, and cord, of a peg having a squared shank and an interposed projection or shoulder rising therefrom, over and upon which the cord bears, as will be hereinafter more fully set forth.

50 Figure 1 represents a front view of the violin with my invention applied thereto; Fig. 2, a side view thereof; Fig. 3, an end view; and Fig. 4, a perspective detail showing the peg, projection or shoulder rising therefrom, and the chin-rest.

55 The body A, having the face A', the neck B, finger-board B', and head B², are all as usual, forming component parts of a violin, to which instrument my invention is herein shown as applied.

50 The instrument is also supplied with any suitable strings, C, passing over a bridge, C', connected with the tail-piece C².

To the lower end of the body of the instrument, in place of the usual peg, a novel peg, to 65 be herein described, is employed, whereby the cord a, which connects the tail-piece to the peg, is retained free from contact with the face A' of the instrument.

70 Referring to Fig. 4, the peg having the head c is provided with a squared shank, c', to prevent its rotation when inserted into the body of the instrument. The cord a is looped around the head c, and its free ends are passed through slots c' c², cut into an interposed projection or 75 shoulder, D, rising from the peg near its head. The free ends of the cord a are then connected with the tail-piece C² in the usual manner. The interposed projection D serves as a bearing 80 for the cord a, and is of sufficient height 80 to bring the cord a entirely free from contact with the face A' of the instrument. By this device the face A' of the instrument is permitted to vibrate its full capacity, as it is obvious from the old construction, wherein the 85 cord a was drawn taut over the edge of the face A', the vibrations of the said face were subdued; and, furthermore, the said cord a, when bearing over the edge of the face A', in the usual manner, subdued the vibrations of 90 the face A' in a direct line taken lengthwise of the said face beneath the bridge, or, in other words, checked the transmission of the vibrations of the essential vibrating portion of the face A'.

95 The device so far described for preventing the cord a from coming in contact with the face A' is equally as well applicable to other stringed instruments.

A chin rest or support, E, of any suitable 100

shape and material desired, is secured to or made integral with the projection D, which projection is of sufficient height to thereby prevent the rest or support E from coming in contact with the face A' of the instrument, and thereby obviating the employment of any suitable fastenings which may be employed to fit a chin-rest to the body of an instrument, the said fastenings bearing usually upon both the 10 face and back, which thereby subdues the vibration of the instrument.

In some instances, should it be only desired to use the chin-rest E occasionally, it may be arranged and constructed to be secured to the 15 projection or shoulder in any adjustable manner, so that it may be readily removed.

I claim—

1. The combination, with the body of a 20 stringed instrument, the tail-piece, and cord by means of which the tail-piece is attached to the said body, of a peg entering the body of the instrument, to which the said cord is attached, and an interposed projection or shoulder rising substantially at right angles there- 25 from, over which the cord passes and upon which it bears when drawn taut, the said pro-

jection or shoulder being of sufficient height to free the face of the instrument from contact with the cord, substantially as described.

2. The combination, with the body of a 30 stringed instrument, its tail-piece and cord, of a peg and an interposed projection or shoulder rising therefrom, over which the cord passes and upon which it bears when drawn taut, and a chin rest or support secured to the 35 said projection or shoulder, thereby preventing either the cord or chin rest or support from coming in contact with the face of the instrument, substantially as described.

3. The combination, with the body of a 40 stringed instrument, its tail-piece and cord, of a peg having a squared shank, and an interposed projection or shoulder rising there- 45 from, over and upon which the cord bears, substantially as described.

In testimony whereof I have signed my name to this specification in the presence of two sub-
scribing witnesses.

MAURICE W. WHITE.
